SAMUEL S. UTTER, OF BROOKLYN, NEW YORK.

Design No. 4,053, dated May 17, 1870.

DESIGN FOR A STOVE.

The Schedule referred to in these Letters Patent and making part of the same

I, SAMUEL S. UTTER, of the city of Brooklyn, county of Kings and State of New York, have invented and produced a new and original Design for a Stove, of which the following is a specification.

The nature of my design is fully represented in the accompanying photographic illustration, to which reference is had.

The principal feature of such design consists in the use of the words "Sweet Home," or their equivalents, either with or without the use of one or more bars of music, composed of notes set in some one of the various

keys; also in the use on such stoves of a monogram substantially as shown in the drawing.

I claim as my invention—

The design for a stove, substantially as described and shown.

SAMUEL S. UTTER.
